US00D565245S

(12) **United States Design Patent** (10) **Patent No.:** **US D565,245 S**
Wonderley (45) **Date of Patent:** **** Mar. 25, 2008**

(54) **SHAVING RAZOR**

D403,811 S 1/1999 Brown et al.

(75) Inventor: **Jeffrey W. Wonderley**, Fort Defiance, VA (US)

(Continued)

(73) Assignee: **American Safety Razor**, Verona, VA (US)

Primary Examiner—Jennifer Rivard
(74) *Attorney, Agent, or Firm*—McDermott Will & Emery LLP

(**) Term: **14 Years**

(57) **CLAIM**

(21) Appl. No.: **29/263,563**

The ornamental design for a shaving razor, substantially as shown and described.

(22) Filed: **Jul. 26, 2006**

DESCRIPTION

(51) **LOC (8) Cl.** **28-03**
(52) **U.S. Cl.** **D28/46**
(58) **Field of Classification Search** D28/44.1-48;
30/32, 34.05, 34.1, 34.2, 41-41.8, 44-45,
30/47-51, 53-58, 526-533, 76-84, 62, 64-66

See application file for complete search history.
